ANCHOR DEVICE FOR CONSTRUCTION BLOCKS

Everett Hollopeter, Rush, N.Y.

Application July 28, 1950, Serial No. 176,294

4 Claims. (Cl. 85—3)

1. A gripping arm assembly for gripping a stud bolt in a hollow building construction block, comprising:

This invention pertains to an anchor for building blocks, and more particularly to an anchor having a pair of oppositely disposed pivotally mounted arms which are mounted in an elongated channel having novel means for urging said arms toward a fully extended position for securing a stud bolt in a hollow building construction block.

Heretofore, expansion bolts and anchorage devices have been employed for the purpose of anchoring securing bolts in desired positions, but various undesirable operational features were frequently inherent therein.

The present invention contemplates, and it is an object thereof to provide a novel anchoring device for building blocks which will be simple in construction, easily operated, efficient in operation, and low cost to manufacture.

A further object of the invention is to provide a construction block anchoring device which has means to permit automatic self-adjustment for centralization of the anchoring device in relation to its pivotal stud bolt with spring-actuated means to permit equalized strain on lateral gripping arms as the device is activated into its final position.

A further object of the invention is to provide an anchoring device for construction blocks wherein a channelized base having pivotally mounted gripping arms as means for automatic centralization of the device as the lateral gripping arms are urged into their final position.

A further object of the invention is to provide a novel channelized anchor for building blocks wherein spring actuated gripping arms tend to centralize the device by permitting lateral movement of a channelized member on the securing bolt.

Further and other objects of the invention may be and may become apparent from a perusal of the present disclosure, and it is to be understood that various changes and modifications may be made in the invention without departing from the spirit of the subjoined claims.

In the drawings:

Fig. 1 is a perspective view partially broken away showing the invention in its normal inoperative position.

Fig. 2 is a side view of the invention in its normal inoperative position, with the gripping arms shown dotted in its operative position.

Fig. 3 is a top view of the invention, partially broken away, in its normally inoperative position, showing the bolt in cross section.

Fig. 4 is an enlarged perspective view, shown in part, of the channelized member before the gripping arms are inserted.

2

Fig. 5 is a perspective view of one of the gripping arm tension springs.

Fig. 6 is a perspective view of one of the gripping arms.

Fig. 7 is a view showing the invention in actual use.

Referring to the drawings there is a C-shaped channel 20 having a pair of oppositely disposed flanges 21 having a bottom portion 22 and a pair of side portions 23 which merge into the flanges 21 on the upper portions thereof and into the bottom 22 at the lower portions thereof.

The extreme ends of the bottom 22 are not as wide as the dimensions between the sides 23, with the end portions terminating in shoulders 24.

Slots 25 are formed in the side portions of each end leaving fingers 26 which may be bent upwardly as shown in Figs. 1 and 2 after the gripping arms 27 are positioned therein.

The gripping arms 27 have shoulders 28 formed on the inner edges thereof and are adapted to fit into the slots 25 so that when the locking fingers 26 are bent upwardly to hold the gripping arms 27 in proper position, the gripping arms may be freely movable therein.

Tension spring 29 is used to retain each of the gripping arms in their normally operative position as shown, urged downwardly, in Fig. 2.

There is a slot 30 formed in each of the gripping arms, which slot is longer in dimension than the head 31 of the tension spring 29, to permit the spring head to be inserted therethrough. A neck 32 of the spring has a smaller dimension than the width of the slot 30 to permit free operation of the gripping arms without binding of the neck 32 against the sides of the slot 30.

The foot 33 is wider than the width of the slot 30 so that when the tension spring 29 is placed in the proper position to hold the gripping arms 27 in their normally operative position, the tension spring will be retained in place by its inherent resiliency, since the head 31 of the tension spring is inclined downwardly at the free edges thereof while the foot of the tension spring 33 is parallel with, and rests flat on the upper surface of the bottom portion 22.

It will be noted that the width of the foot is slightly less in dimension than the width between the sides of the inner surfaces thereof. This is desirable since the spring foot may have a length along the edge 34 sufficient to permit a slight lateral movement only, of the spring during period of time before and while the anchoring device is being inserted and manipulated through its final gripping operation in conjunction with the construction block.

It will be noted that there is a space 35 between the locking fingers 26 and the side portions, adjacent the ends of the bottom 22. This space permits the locking fingers to be gripped by a tool and into a position for either locking or unlocking the shoulders 28 within slots 25 without appreciable likelihood of the locking fingers 26 binding on the base.

An elongated slot 36 is of sufficient width to permit free movement of the stud bolt 37 to move laterally within the slot without frictional engagement between the stud 37 and the sides of the slot 36. The length of the slot 36 is sufficient to permit a wide latitude of movement between the stud 37 and the slot of the channel 20 so that there will be automatic centralization of the channel on the stud as the device is placed in position and is in process of being tightened.

Fig. 2 shows the side wall 38, dotted, of a construction block, with the gripping arms 27, shown dotted, as the serrated edges 39 or teeth bite into the sides of the construction block.

In operation, members of wood 40 will have holes drilled therein to receive the studs 37. After the studs are inserted through the holes in the wood 40, the threaded portion of the studs 37 are threadedly connected to the secured nut 41 which fits between the sides 23, and may loosely engage the bottom 22, when inoperative position, but which definitely engages the underneath surface of the flanges 21 when the stud bolt 37 is tightened.

Due to the width of the gripping arms 27, when the anchor is placed within the hollow portion 42 of the construction block, the anchor will slide downwardly within the hollow of the construction block while the teeth 39 ride on the construction block side walls.

After tension is placed on the stud 37 to urge the anchor outwardly, the serrated edges of the gripping arms 27 will bite into the construction block and continue to be forced therein as the serrated edges are frictionally held in engagement with the construction block while the remainder of the anchor is drawn outwardly by the tightening action of the stud. The lip 43 acts as a limiting means to retard the downward movement of the arm 27.

From the foregoing it will be seen that the anchor device is simple in operation and positive in action, and that there is a wide latitude for automatic centralization of the anchor device in relation to the stud. It is pointed out that the lower end of the stud 37 will always emerge below the bottom portion 22 of the anchor so that the length of the slot 36, by engagement with the stud 37 will act as a limiting means for restricting the lateral movement of the nut 31 within the channel 20.

What is claimed as new and desired to be secured by Letters Patent of the United States is:

1. An anchor of the class described having a channel consisting of a base having an elongated

slot therein, a pair of sides secured on said base, and a flange formed on each edge of said channel, a pair of locking fingers formed on each end of said channel, a pair of gripping arms each having an aperture formed therein, a pair of shoulders on each of said gripping arms adapted to be pivotally mounted on said channel and held thereto by said locking fingers, and means formed on the outer edge of each of said gripping arms adapted to engage the wall of a construction block; tension means adapted to be inserted through the aperture in each of the gripping arms and adapted to engage the channel for urging said gripping arms to an operative position, a nut slidably mounted within the channel, and a threaded stud connectable to said nut and extending through the base slot.

2. An anchor of the class described having a channel consisting of a base having an elongated slot therein, a pair of sides secured on said base, and a flange formed on each of said sides; a pair of locking fingers formed on each end of said channel, a pair of gripping arms each having an aperture formed therein, a pair of shoulders on each of said gripping arms adapted to be pivotally mounted on said channel and held thereto by said locking fingers, and means formed on the outer edge of each of said gripping arms and adapted to engage the channel for urging said gripping arms to an operative position, a nut securing means slidably mounted within the channel, and stud means connectable to said nut and securing means and extending through the base slot.

3. An anchor device having a channel with an aperture therein, a nut slidably mounted in said channel, a gripping arm pivotally mounted on each end of said channel, resilient means for holding said gripping arms in a normal operative position, and a threaded stud insertable in said nut and extendable through said aperture.

4. An anchor device having a C-shaped channel with a slot formed therein, a nut slidably mounted in said C-shaped channel, a gripping arm pivotally mounted on each end of said channel, resilient means for holding said gripping arms in a normal operative position, and means connectable to said nut and protruding through said aperture for operating said gripping means.
